TOP CONSTRUCTION FOR HOSIERY

Jacob A. Goodman, Indianapolis, Ind.

Application May 4, 1933, Serial No. 669,403

6 Claims. (Cl. 66—172)

This invention relates to hosiery and has particular reference to an improved top construction possessing various qualities and characteristics which render the same of great utility. 5 The invention is primarily applicable to hosiery—such as men's socks—which terminates below the knee and which is difficult to support in proper position on the leg. I have discovered that by constructing the upper portion of the hose in the 10 particular manner hereafter described the same may be made to stay in proper position. The invention is particularly suited to the type of article generally designated as "self-supporting", within which category are included socks and 15 knee-length stockings.

In hosiery of the type mentioned, it has always been conventional so far as I am aware to provide knitted tops of heavy fabric, usually ribbed, and in some cases comprising two plies. Such a top, 20 because of its weight, tends to work down the leg. Further, because of the relative inelasticity resulting from its heavy texture and the substantial stretch which is ordinarily necessary in order to make it conform to the diameter of the 25 larger portion of the leg which it overlies, the same tends to gradually creep down the leg as the muscles are flexed to a portion of the leg of smaller diameter.

The present invention constitutes a substantial 30 departure from known practices in that instead of using heavy fabric in the top of the hose a light weight and relatively elastic fabric is provided. As hereafter more fully explained, the top is constructed of relatively light weight yarn 35 and in such manner that the same will not exert any circumferential tension on the leg or manifest any appreciable tendency to fall down of its own weight.

The invention will be described as applied to 40 men's socks, but it will be understood that the same is equally applicable to other types of hosiery for men, women and children, which cover the enlarged calf area of the leg but terminate at some point below the knee. As a matter of 45 terminology I have found it convenient in setting forth the application of the invention to use the terms "sock", "knee-length stocking" and "short-length stocking" to designate generally the various types of hosiery in connection with which the invention may be employed.

In the drawing:

Fig. 1 is a diagrammatic representation of a 50 sock having a top provided at its end with a short supporting band, the same being generally

similar to conventional socks except as to features explained in the specification;

Fig. 2 is a view similar to Fig. 4 of a sock of the self-supporting type made in accordance with the present invention showing the article on the 5 leg;

Fig. 3 is a sectional fragmentary view, the same being a detailed illustration of one form of edge band which may be utilized in the sock shown in Figs. 1 and 2; and, 10

Fig. 4 is a view similar to Fig. 3, showing a further type of edge band which may be used.

It is immaterial whether the hose to which the invention is to be applied is circular knit or of full fashioned type, since my top construction 15 may be made on either kind of machine. As indicated, the characteristic feature of the present invention is the provision of top fabric which is light in weight, readily stretchable and of elastic character, and of such low resiliency as to exert 20 little if any circumferential tension on the portion of the leg which it covers. The leg, or body, fabric may be of either heavy or light texture, and may be composed of any of the usual materials, such as silk, artificial silk, wool or cotton. 25 If the leg fabric is of light weight the top fabric may be composed of the same thread and generally similar in character thereto. Unless, however, the body fabric is more or less sheer, I find it desirable to use lighter fabric in the top portion 30 than in the leg portion.

Referring now to Fig. 1, I have therein indicated a sock comprising a body or leg lower portion 10 knit in the usual manner with a close texture and having a normal amount of inherent 35 resiliency adapting the same to snugly fit the thinner part of the leg below the enlarged calf area. Adjoining the same is a top or upper leg portion adapted to cover the enlarged calf area and terminating below the knee. The relative 40 lengths of the two portions may vary to some degree, and I do not wish to limit myself to any particular length of top. To be effective the top should, of course, be of substantial length, corresponding generally in its length to the extent 45 of the thicker calf area. It will be evident, however, that the line of demarkation in Fig. 1 between the top fabric and the body fabric should not be taken as definitely indicating the proportional lengths of the leg and top fabric. It may be stated, in any event, that the length of the top 50 should be an appreciable factor in the total length of the article.

In knitting the top section 11, single ply fabric comprising a relatively lightweight yarn is used. 55

The lighter the thread and the fabric the better will be the results. The limit of lightness of the thread will be determined only by the durability which it is desired to impart to the top fabric.

5 Various kinds of yarns may be used such as silk, mercerized cotton and rayon. The heavier the thread used, the greater will be the weight of the fabric. From tests conducted, it now appears to me that satisfactory results may be obtained 10 by using yarn as heavy as 12-thread silk and number 60/2 mercerized cotton, or their equivalents. As just indicated, the limit of lightness is determined solely by the matter of durability, but I may say that relatively light silk of 5 or 6 15 threads and equivalent weights of cotton, such as 120 Egyptian lisle, appear practical. Where lighter weights of cotton are used it is preferable to use the imported long staple article so that the thread will have the necessary tensile strength.

20 In making the top the thread is knit under relatively low tension so as to increase the elasticity of the fabric and thus enable the same to be easily stretched. While it is desirable to knit the fabric loosely, it is preferable as a matter 25 of appearance and shape to avoid sleaziness, and to this end I find it well to employ relatively fine gauge knitting machines. Of course, where the leg fabric is knit on a fine gauge machine, as in the case of silk socks, the top will be knit on the 30 same machine as the leg fabric and integrally therewith, it being preferable to decrease the tension on the thread feed during the course of knitting of the top. As pointed out above, the same thread may be used in the top as in the leg 35 fabric when the latter is constituted of the lighter weight yarns, or again, it may be lighter thread. By knitting the top portion with an appreciably lower tension the same will be of substantially looser texture and more stretchable than the lower leg fabric which, as normally, will be closely 40 knit and resilient to snugly fit the thinner part of the leg below the enlarged calf area.

Any knit fabric, whether light or heavy, possesses a certain degree of elasticity and stretch. 45 The fabric also, however, is resilient in that when stretched there is a tendency of the fabric to contract to normal size. The resiliency is greater the heavier the fabric and the coarser the yarn. Also the more closely formed the knitted loops 50 of the fabric the less will be the ability of the fabric to stretch and the greater will be its resiliency. In order to avoid circumferential tension which tends to cause a stocking to work down the tapering parts of the leg I deem it necessary to make the top in such manner that the resiliency of the fabric is very low and insufficient to cause any appreciable tendency of the top to contract when on the leg. That is to say, I desire the top to be elastic in the sense that it 55 will readily yield or stretch to loosely conform to the diameter of the leg but without any substantial tendency to recoil to its normal diameter. In some respects, therefore the top fabric is similar in character to sleazy fabric. By making the top fabric lightweight and of loose texture I can get the desired stretch and at the same time the resiliency will be at a minimum and less than that of the normally resilient lower leg portion.

60 At the upper open end of the loosely fitting top or upper leg portion 11 of the article is a supporting band 12 engageable with the leg above the point of largest diameter but at a point below the knee. Such band is both elastic and 65 resilient in character, snugly fitting the leg and 70

75

rendering the sock or stocking self-supporting. The band may be of double ply and in the form of a turned welt or constitute reinforced single ply fabric. As will be noted in the drawing the band may be relatively narrow. This is desirable 5 in order to keep down weight and for leg comfort. Also, because the upper leg portion 11 is loosely fitting and of light weight, the same does not readily tend to either fall or work down the calf area and a narrow band gives adequate support. 10

By knitting the top fabric 10 with low tension, the same will tend to have a normal diameter somewhat larger than the leg fabric besides being more stretchable due to the looser texture resulting from the low tension. This is 15 quite desirable, since the top fabric overlies a larger part of the leg than the leg fabric, and the less stretch that is necessary in the top the less will be the circumferential tension when the sock is worn which tends to cause the fabric to creep 20 down the leg. If the leg fabric is knit to a relatively small diameter on a relatively few needles, it might be considered desirable to use a larger number of needles in knitting at least the main portion of the top fabric. Under any circumstances it will be understood that it is desirable 25 to take whatever expedients are necessary in order to shape the top fabric so that it does not have to be stretched excessively to attain the actual diameter of the calf, and make the fabric 30 thereof of such texture that the top will possess little resiliency and loosely fit the calf without appreciable binding tension thereon.

If a yarn were used in knitting the top which tended to shrink under dyeing and washing, it 35 is obvious that the diameter of the top would eventually become small and such as to require considerable stretch in order to obtain leg diameter. For this reason, it is deemed important to utilize yarn which is substantially fixed in 40 length before knitting. I deem it advisable, therefore, to knit the top of yarn which has been preshrunk. Such yarns are in themselves well known, and since the production thereof forms no part of the present invention, a description of 45 preshrinking processes appears unnecessary.

The top fabric may be plain knit as indicated in Fig. 1. It will be understood, however, that I do not confine myself to any particular type of knitting so long as the top fabric is made to 50 incorporate the physical characteristics herein set forth which will provide a light weight loosely fitting top portion.

Because my hose top is lighter in weight than conventional and avoids circumferential tension, 55 it possesses a great advantage over the usual heavy reinforced or ribbed top construction. Self-supporting socks and stockings are in themselves well known but have been generally unsuccessful. So far as I am aware such articles 60 have always been made with a relatively heavy or ribbed top which exerts considerable circumferential tension such as causes the same to creep down the tapering part of the human leg and the top because of its own weight also tends 65 to fall down. Because of these difficulties trouble has been experienced in making articles which would stay up without incorporating some sort of supporting band which exerted such a high degree of circumferential tension as to be 70 injurious to the leg and retard the circulation of blood therein.

The sock of Fig. 2, which I now regard as the preferred embodiment of my invention, includes a top portion 14, a supporting band 15 and a 75

body or leg portion 16. The top will be of the same character as the top 11 in Fig. 1, comprising light weight single ply and elastic fabric, preferably plain knit of light preshrunk yarn, 5 and formed integrally with the body portion 16. While not entirely necessary, the supporting band 15 will desirably be located at the extreme upper end of the top.

It will be obvious to those familiar with the self-supporting type of hosiery that the supporting band may take a variety of forms and either be formed integrally with the top or fastened thereto. It should be pointed out, however, that because of the character of my top the band need 15 exert only a slight circumferential tension on the leg. That is to say, a sock embodying my invention tends naturally to stay up on the leg and there is no necessity of making the band so heavy and tight as to bind the leg and retard 20 circulation as is the case with known self-supporting hosiery, but it will be understood that because of its supporting function the band must be more resilient than the loosely fitting top portion to the upper edge of which it is secured.

25 As a matter of preference and with the view of making a sock which is neat and generally similar in appearance to hosiery which does not embody self-supporting features, I knit the resilient band 15 integrally with the top. With 30 the development of a satisfactory light rubber yarn I find that the band may be made of such material, which by reason of its natural elasticity and that inherent in knit fabric admirably suits my purpose. Again, I find that the band 35 may be made of wool yarn. While not possessing the elasticity or tensile strength of the rubber yarn, the wool presents a rougher surface which tends to cling to the leg and has sufficient resiliency for use as a supporting band with the 40 special top fabric. A combination of both rubber and wool may be resorted to if desired.

Since the tension to be exerted by the elastic band can be quite low the same need not be heavy or wide. It may be double ply as indicated at 15a in Fig. 3 and formed during the course of knitting in a manner similar to that employed in making turned welts, or it may be embodied as a single ply strip 15b as shown in Fig. 4. Other forms of bands will readily suggest themselves to those skilled in the art, so it 50 will be understood that the ones described are given only as particularly desirable types.

Instead of using plain knit fabric in the top of the sock, the embodiment of Fig. 3 may be employed as a self-supporting sock with the elastic band 15 of any desired type in association with the open mesh top 13.

For best results in self-supporting half hose, the top and body portions should be proportioned as generally shown in Fig. 2. The body or lower leg portion 16 will extend up over the thinner lower part of the leg to the point where the diameter of the leg begins to increase at the calf. The light elastic top fabric will begin at 60 this point so that there will be no appreciable circumferential tension due to the larger size of the leg therebeyond. As heretofore pointed out, it is desirable to knit the top looser than the leg fabric and if the leg is knit to a relatively small diameter it will also be advisable to knit the top with an increased diameter. To enable 65 the supporting band to operate to best advantage the top should be of such length as to extend 70 above the point of largest diameter in the calf

so that the band 15 will encircle the smaller portion of the leg upwardly of the calf.

The present invention for the reasons set forth above enables a self-supporting hose to be constructed far superior both in comfort and supporting qualities to known articles of such type. Because it does not cling to or exert any appreciable pressure or binding tension on the leg it is far more comfortable. Because of its light texture the same is cool and therefore specially desirable in summer. Again, because of its light weight and inherent elasticity the top fabric facilitates the pulling on and removing of the sock over the heel of the wearer. Besides these and other advantages, the top is superior to 15 known articles in the use of yarn of fixed size which prevents the top from shrinking in diameter on dyeing or washing and for this reason insures a proper fit at all times without binding.

I claim:

1. A self-supporting short length knitted stocking including a tight knit fabric leg portion of such length as to terminate short of the enlarged calf area of the human leg, an adjoining fabric top portion adapted to overlie said enlarged calf area, and a resilient supporting garter band secured to the upper end of the top portion so as to grip the leg at a point above the enlarged calf area, said top portion comprising a single ply of light weight relatively sheer and unreinforced fabric fabricated throughout its circumference with a loose and uniform knitted texture and composed throughout of light weight yarn.

2. A self-supporting sock including a normal closely knit resilient lower leg portion adapted to snugly fit the thinner lower part of the leg below the calf, an adjoining ribless, single ply, knitted top portion adapted to extend up over the enlarged calf area and adapted to loosely fit such area, said top portion throughout its circumference being more stretchable and less springy or resilient than the lower leg portion, and being composed of loose textured fabric capable of substantial stretch but of such low resiliency as to tend to stay stretched and lacking sufficient contractility to tend to return to its original unstretched condition or exert any appreciable circumferential tension around the calf, and a resilient garter band adapted to engage the smaller part of the leg above the calf joined to the upper 50 end of the loosely fitting calf portion.

3. A knitted sock or stocking of substantially knee-length having a resilient garter band at its upper end engageable with the leg above the area of greatest diameter, and including a closely knit lower leg portion adapted to snugly fit the thinner part of the leg below the enlarged calf area, and an unreinforced upper loosely fitting calf portion knit to a larger diameter than the lower leg portion of light weight yarn, said upper portion being 60 of light easily stretchable texture less resilient than the lower leg portion and conformable to the contour of the calf area without exerting any appreciable circumferential binding tension 65 thereon.

4. A self-supporting knitted sock or stocking including a lower leg portion closely knit to snugly fit the thinner part of the leg below the enlarged calf area, an upper loosely fitting portion adapted 70 to extend up over the enlarged calf area but terminating short of the knee which is easily stretchable to shape and of less resilient texture than the lower leg portion and constituted of relatively fine yarn of lighter weight than the yarn in the lower 75

leg portion, and a resilient garter band at the open end of the upper portion engageable with the leg above the area of largest diameter.

5. A knitted sock or knee-length stocking including a lower leg portion adapted to snugly fit the thinner part of the leg below the enlarged calf area, an adjoining substantially non-shrinkable upper portion knit to a larger diameter than the lower leg portion adapted to loosely fit the enlarged calf area, said upper portion comprising thin single ply fabric of light weight preshrunk yarn and being of looser knitted texture, more stretchable and less resilient than the lower leg fabric, and a resilient garter band at the open end

of the upper portion engageable with the leg above the area of greatest diameter.

6. A knitted sock or knee-length stocking having a resilient garter band at its upper end engageable with the leg above the area of largest diameter, and including a closely knit silk fabric lower leg portion adapted to snugly fit the thinner part of the leg below the enlarged calf area, and an adjoining upper loosely fitting calf portion knit to a larger diameter and of looser more 10 stretchable and less resilient knitted texture than the lower leg portion and comprising thin single ply fabric of light weight cotton yarn.

JACOB A. GOODMAN.
